UNITED STATES PATENT OFFICE.

CHARLES A. WEISS, OF BROOKLYN, NEW YORK, ASSIGNOR, BY MESNE ASSIGNMENTS, TO MASON STEAM SYSTEM, INC., OF NEW YORK, N. Y., A CORPORATION OF NEW YORK.

CLOTH-STEAM-SPONGING DEVICE.

1,239,991.

Specification of Letters Patent. Patented Sept. 11, 1917.

Application filed July 24, 1914. Serial No. 852,949.

To all whom it may concern:

Be it known that I, CHARLES A. WEISS, a citizen of the United States, and a resident of the city of New York, borough of Brooklyn, in the county of Kings and State of New York, have invented a new and Improved Cloth-Steam-Sponging Device, of which the following is a full, clear, and exact description.

10 This invention relates to apparatus for treating cloth in clothing factories or tailoring establishments, and has particular reference to means for steaming various widths of cloth in a safe and reliable manner, the 15 operation being performed most expeditiously and with a minimum expenditure of time and fuel.

Among the objects of the invention, therefore, is to provide a steam generator of a 20 construction adapted especially for most effective and convenient use.

The foregoing and other objects of the invention will hereinafter be more fully described and claimed, and illustrated in the 25 drawings forming a part of this specification, in which like characters of reference indicate corresponding parts in both the views, and in which—

Figure 1 is a vertical sectional view of the 30 complete invention; and

Fig. 2 is a vertical sectional detail of the gas valve indicating a conventional pilot feature.

The several parts of the device may be 35 made of any suitable materials, and the relative sizes and proportions, as well as the general design of the mechanism, may be varied to a considerable extent without departing from the spirit of the invention hereinafter more fully described and specifically 40 claimed.

Referring more particularly to the drawing I show an apparatus including a steam generator A and a cloth treating table B intimately associated with each other and having a steam conveying pipe C leading from one to the other.

The generator is illustrated as comprising 45 a substantially closed boiler or heater 10 closed within a casing 11. A source of heat 50 12, shown in the nature of a gas burner, is

located within the casing below the boiler, the heat from which is adapted to play either directly upon the bottom of the boiler or upon a water coil 13 having one end communicating directly with the bottom of the boiler at 14 and the other end of the coil projecting through the bottom of the boiler at 15 and opening upwardly within the boiler, as shown at 16. The interior of the casing 55 may be lined with asbestos 17 to protect the same from the intense heat and to confine the heat therein as much as possible, provision being made, however, for the heat to pass upwardly through the perforated top 18 60 of the casing so that a certain portion of the heat will be directed against the false bottom of a preheater or tank 19 supported above the boiler 10. A pipe 20 serves to provide communication between the preheater 65 19 and the boiler. This pipe is fitted with a normally closed stop cock 21 to which is connected a crank or arm 22. A pipe 23 serves to convey gas or the like to the burner 12 and in this pipe is mounted a normally open 70 stop cock 24 having a crank or arm 25. A link 26 is arranged between the arms 22 and 25 through which, by manipulation of a handle 27, both stop cocks may be moved simultaneously as suggested by dot and dash 75 lines in Fig. 1. The heating apparatus described herein is of a very intense nature and intended for rapid generation of steam. Consequently the boiler will ordinarily 80 carry a considerable quantity of steam while the machine is in operation. This steam would tend ordinarily to interfere with or prevent the flow of water through the pipe 20 from the tank to the boiler and this is why the normal flow of gas is cut off at the 85 valve 24 when the valve 21 is opened. I show at 28 a gage glass on the outside of the casing 11 for the purpose of indicating the depth of the water in the boiler 10, said glass being in communication with the upper 90 and lower portions of the boiler by means of pipes 29 and 30 respectively.

With the steam generator arranged as shown, and with a sufficient supply of water in the boiler 10, heat from the burner 12 will 100 cause the water to boil and produce steam which may be conveyed therefrom to the

cloth table through the pipe C. The coil 13 arranged between the boiler and the burner provides for rapid generation of steam, some of which may pass through the pipe C 5 and another portion of which may act upon the water within the boiler to transform the same into steam. When the supply of water in the boiler requires replenishing, the valve 21 may be opened to allow the water already 10 partially heated in the tank 19 to flow downwardly into the boiler, and at this time the flow of gas through the pipe 23 may be shut off. When the valve 21 is again closed the flame at the burner may exert its maximum 15 influence. The flow of gas through the pipe 23 just referred to means the normal flow for the generation of steam and has nothing whatever to do with the use of a pilot 24' to maintain a taper of flame to re-ignite a 20 normal flow of gas after the valve 24 is opened and the valve 21 closed. Any suitable valve 24' in or associated with the pipe 23 may be employed to shut off the flow of gas from the pipe 23 when the improved 25 device described herein is out of use.

The cloth treating table B comprises any suitable form of supporting means shown as crossed legs 31 arranged in pairs and pivoted together on pivots 32 in axial alignment with each other. The water of condensation which may collect in the gutter 35 beneath the table top may be discharged through a drain pipe 35'.

At 37 I show a distributor in the form of 25 a tube having perforations 37' along its upper surface. This distributor is supported by any suitable means within the gutter 35 and substantially between and parallel to the side walls 36. The steam pipe C leads 30 into one end of the distributor and the other end of the distributor is closed. A shield comprising two parts, namely, a cap 38 and a plate 39, co-operates with the distributor along the upper portion of the 35 gutter for the purpose of confining the steam to a certain portion of the gutter according to the width of the cloth being treated. The cap 38 conforms to the upper surface of the distributor and is adapted 40 to close certain of the holes 37'. Said cap is connected to and is carried by the plate 39 which is adapted to slide along the upper portion of the gutter.

Any suitable number and form of supporting and reinforcing members 47 for the 45 steam generator may be provided. As shown, however, one of these supporting members is provided with holes C', 29' and 30' whereby the respective pipes C, 29 and 50 30 have direct and positive support. These legs or supports 47 extend upwardly through the casing 11 and preferably between the inner wall of the casing and the asbestos lining 17 therefor. By fitting the

gage glass to the generator on the side 65 thereof adjacent the steam distributor, it will always be in view of the operator who is stationed likewise adjacent the distributor. The purpose of the false bottom 19' of the pre-heater is to prevent the water of 70 condensation from forming on the top of the tank. The casing is provided with a closed bottom 11' to prevent the heat from striking downwardly against the main support of the structure. It is to be noted that 75 the apparatus may be used to good advantage for any other purposes than those already set forth, as, for instance, the evaporating of medicaments, sterilizing of 80 towels, humidifying, etc.

Having thus described my invention, I claim as new and desire to secure by Letters Patent:—

1. The herein described steam generator comprising a boiler, means to heat water 85 within the boiler, said heating means including a pipe for fluid fuel, a normally open valve controlling the normal flow of fuel through the pipe and including a bell crank handle, a preheating boiler supported 90 above the main boiler, a pipe leading from one boiler to the other, a normally closed valve for controlling the flow of water through said pipe, an arm connected to the last mentioned valve, and a bar leading 95 from the valve arm just mentioned at a point above the primary boiler down to the bell crank handle aforesaid, the parts being so arranged that when the handle is moved to shut off the normal flow of fuel the water 100 pipe will be opened, substantially as set forth.

2. A steam generator comprising a casing having a perforated dome-shaped top, an imperforate bottom and a heat insulating 105 lining to its body portion, supporting means for said generator, said means comprising legs extending upwardly within the casing between its vertical walls and the heat insulating lining and through the top of the 110 casing, a preheater supported on said legs above the casing and spaced therefrom, a boiler proper within the casing and supported therein by pipes passing through one of the aforesaid supporting legs, a fluid fuel 115 heater in the lower portion of the casing and below the boiler, a water coil associated with the boiler and having a portion of the coil within the boiler, and a portion exterior to the same and between the heater and 120 the boiler, a pipe connecting the bottom of the preheater with the top of the boiler, a valve controlling the same, said valve normally closed, an arm projecting from said valve, a link flexibly connected to said arm, a fluid fuel inlet at the lower portion of the 125 casing and communicating with the aforesaid heater, a valve controlling said inlet,

said valve being normally open, a handle connected to said valve, and also to the link extending from the valve between the boiler and preheater, and a steam outlet

5 pipe extending transversely from the dome of the boiler between the casing and the preheater.

In testimony whereof I have signed my name to this specification in the presence of two subscribing witnesses.
